UNITED STATES PATENT OFFICE

JOHN F. KILLION, OF ATTLEBORO, MASSACHUSETTS.

KEY-RING.

1,165,882.

Specification of Letters Patent. Patented Dec. 28, 1915.

Application filed September 9, 1915. Serial No. 49,812.

To all whom it may concern:

Be it known that I, JOHN F. KILLION, citizen of the United States, and resident of the city of Attleboro, in the county of 5 Bristol and State of Massachusetts, have invented certain new and useful Improvements in Key-Rings, of which the following is a specification.

This invention relates to key rings, and 10 has for its object to provide a ring for carrying keys and having two separate loops, one for the main bunch of keys and the other for the key which is of special importance to separate it from the rest.

15 A further object of this invention is the simplicity, durability and practicability in the construction of such a ring which is that of providing a body portion having a main loop and an auxiliary loop each formed of 20 spring wire and having one of their ends pivoted in said body, the free end of each being adapted to swing open to receive the keys and then swing back to be engaged and held in said body portion.

25 With these and other objects in view, the invention consists of certain novel features of construction, as will be more fully described, and particularly pointed out in the appended claims.

30 In the accompanying drawings: Figure 1— is a side elevation showing my compound key ring with the two separate key receiving loops in closed position. Fig. 2— is a side elevation showing the two key receiving loop members in open position ready 35 to receive the keys, and the body portion partly in section. Fig. 3— is a perspective view showing the body portion which is substantially U shaped in cross section.

40 Referring to the drawings 10 designates the body portion which is preferably constructed of a strip of sheet metal bent into substantially U shape in cross section, the same having two side walls and a bridge 45 portion 11 which latter is provided with openings 12 and 13 therethrough.

The main loop member 14 is preferably constructed of wire preferably square in cross section one end 15 being pivoted at 16 50 between the side walls 17 of the body member, the free end 18 of this wire loop being notched as at 19 thus forming a protuberance 20 at the end thereof, the wire itself being preferably of spring metal and the 55 ends normally stand apart a distance greater than the width of the body portion, whereby

when it is desired to close this loop it is necessary to spring the end 18 inward and swing the whole so as to bring the protuberance inside of the body portion and pass 60 the same into the opening 13 in the bridge portion. The inherent spring in the wire forcing the protuberance into the opening thereby securely locking this free end into the body portion.

65

A feature of my invention is that in addition to providing a large loop for carrying the bulk of the bunch of keys, I have provided a smaller loop 20 which serves a double purpose, first this latter loop is 70 adapted for carrying the special key which it is desired to separate from the bunch, such for instance, as the latch key for the house, whereby it may be readily selected by the sense of touch when the keys are 75 taken from the pocket at night. A further object of this auxiliary loop is that it serves as a bale to which the key chain 21 may be attached. The construction of this smaller loop member is similar to that of the larger 80 loop member, as it has one end 22 pivoted at 23 in the body portion, and its opposite end is notched as at 24, providing a protuberance 25, and the wire of the loop is made of spring material, whereby when it 85 is desired to close the same the free end is pressed inward and swung downward to carry the same into the body portion and cause the protuberance 25 to enter the opening 90 90 95 95 95 100 100 105 110

By this construction it will be seen that the ring is formed of but three parts which constitute, the two loop wires and the body portion, thus forming a compound key ring that is very neat in appearance, strong and durable and inexpensive in construction, yet one which is adapted to separate the special key from the bunch. When it is desired to open either of the loop members the same is grasped between the thumb and finger and pressed inward to contract the loop and withdraw the protuberance from engagement with its opening.

It is not intended to limit this invention to the specific construction and arrangement herein shown and described as the details of construction may be varied without departing from the spirit and scope of my invention.

I claim:

1. A key ring comprising a body member, a main loop member and an auxiliary loop

member, each formed of spring wire and each pivoted independently of each other at one of their ends in said body, the opposite ends of each loop being adapted to enter said body and means in said body for securely retaining the ends of said loops therein.

2. A key ring of the class described, comprising a body member having two sides joined by a bridge portion, a main loop and an auxiliary loop both of spring wire, each

having one end pivoted between said sides, the free end of each being adapted to enter said body and engage the bridge portion thereof and be retained therein by pressure 15 of the inherent spring in the wire.

In testimony whereof I affix my signature in presence of two witnesses.

JOHN F. KILLION.

Witnesses:

HOWARD E. BARBA,
A. F. MACREADY.
